SUCTION DEVICE

James Harmon Tanner, Kirribilli, near Sydney,
and William Francis Tanner, Fivedock, near
Sydney, Australia

Application September 11, 1935, Serial No. 40,098
In Australia September 12, 1934

1 Claim. (Cl. 103—262)

This invention relates to an improved suction apparatus of the type wherein the flow of gas or liquid past an orifice creates a reduction of pressure at the mouth of the said orifice. Amongst 5 the objects of the invention is to furnish a device wherein a greater degree of vacuum, or suction, is obtained than with devices of the same type already in existence so that it may be applied to operations requiring the creation of vacuum, 10 or suction, in a more efficient manner than heretofore and, by virtue of its increased efficiency, to operations wherein existing apparatus of similar type is unsatisfactory. Further objects are to dispose of the effluent in a more satisfactory manner than heretofore achieved, and to provide 15 means rendering the device readily adaptable to varying conditions of use. The device is particularly useful in dental operations for ejecting fluid, such as blood and saliva, from the mouth of the patient, or for ejecting blood, pus, and the like from wounds or incisions during surgical operations. However, the invention is by no means limited in its application to such uses and it will be obvious that it may be utilized for the purposes 20 of suction apparatus in general as, for example, in drawing fluids from a container, or chamber, or in creating a certain degree of vacuum in a container, or chamber, and so forth.

Hitherto, apparatus of the type referred to has 25 not proved satisfactory for the ejection of blood and the like from wounds and for many other purposes since a sufficient degree of suction could not be obtained thereby. The present invention 30 contemplates the provision of a device which is simple, inexpensive, readily portable and capable of being used in a confined space, by means of which the necessary vacuum may be created for the purposes herein specified and by means of which fluid, or the like, drawn through the 35 device, may be readily and cleanly disposed of.

In the accompanying drawing which illustrates a satisfactory form of the invention—

Figure 1 is a side view of the device,

Figure 2 is a longitudinal section through the 40 tubular member, referred to hereinafter,

Figure 3 is a longitudinal section through the tubular member along the line A—A of Figure 2,

Figure 4 is a plan view of the suction device,

Figure 5 is a longitudinal section through the 45 discharge chamber viewed from the discharging side thereof,

Figure 6 is a longitudinal section through the discharge chamber along the line B—B of Figure 5, and

Figure 7 is a plan view of the discharge chamber.

The apparatus consists of a suitable inlet device 10, which conducts fluid, such as water, into the tubular member 11, and ejects it through a tube, or the like 12, terminating in a discharge device 13, of particular construction. The chamber 13 is not essential to the improved suction effect, but ensures a satisfactory disposal of the discharge.

The tubular member 11 consists of a conical shaped inlet 14 converging at its downward end. The conical inlet 14 leads into a conical shaped outlet 15, which converges at its upper end. As will be seen from Figures 2 and 3 of the drawing, the bore of the flared outlet 15 is greater than that of the flared inlet 14 at their point of junction. Fluid, passing through the tubular member 11, flows past the orifice 16, of a suction tube 17, said orifice 16 being located in the outlet portion 15 of the tubular member 11. The conical sections of the inlet 14 and outlet 15 are such, and the orifice 16 is so located, that fluid passing through the tubular member 11 impinges upon the side 15a of the outlet 15 at a position below the orifice 16. In this way a partial vacuum is created across the suction orifice 16 and an enhanced suction effect is obtained. It has been found that by reducing the bore, or taper, of the outlet 15 in relation to that of the inlet 14 an improved 20 suction effect is achieved and that this increases directly in relation to the diminution in bore, or taper, of the outlet 15. The suction tube 17 may be produced, or fitted with an extension tube, which may be rigid or flexible, for the purpose of conducting it to the desired location.

The tube 12, which may be rigid or flexible, and may be composed of a flexible metal which allows it to be bent to any desired shape that convenience may direct, terminates in a discharge chamber 13 which is slotted, as shown at 25 18. These slots are not limited in number and may be positioned elsewhere in the chamber 18, as at the foot thereof. The slots 18 show an approved method of allowing fluid egress from the chamber 13 and may be positioned longitudinally, or other suitable means of breaking the stream of fluid passing from the chamber 13 may be employed. Within the chamber 13 is situated a post or pedestal 19, which functions to scatter the stream of fluid passing from the tube 12. The chamber 13 may be furnished with a detachable bottom plate for the purpose of ready cleaning. The discharge chamber is 30 35 40 45 50 55

fashioned, as described, for the purpose of breaking the flow of fluid through the device, preventing the splashing of such fluid, and readily ejecting it from the device.

5 In operation the inlet 10 of the device is attached, by suitable means, to source of fluid or gas supply and incoming fluid or gas, passing through the tubular member 11 creates a reduction of pressure across the orifice 16 of the 10 tube 17 causing a suction to take place therein. The discharge passes through the tube 12, impinges upon the pedestal 19 and runs to waste without unnecessary splashing through outlets 18. In the application of the device to dental 15 purposes the inlet 10 may be attached to any conveniently disposed water tap, such as a tap placed over a wash basin, so that the device may rest in the wash basin. By making the tube 12 of flexible material it can be twisted to fit 20 conveniently into any wash basin of usual construction. Suitable attaching means, of known type, are provided so that the device may be attached to any tap of usual design. Such attaching means are well known and will not be 25 described herein since they do not form part of the present invention. The tube 17 is attached to a saliva ejector which is placed in the mouth of the patient for the ejection of saliva, blood, pus, and the like. When water flows through the 30 device ejected matter from the mouth of the patient is drawn through the tube 17 into the pipe 12 and runs to waste with water from the inlet 10 through the outlets 18. The construc-

tion of the housing 13 is such that splashing, which is both unsatisfactory and insanitary, is considerably minimized.

Although the device has been described with particular reference to its use in dental operations, it will be obvious that its scope is not so limited and numerous other applications of the device will be readily apparent.

Having thus described and ascertained our 10 said invention and the manner in which it is to be performed we declare that what we claim as new and desire to secure by Letters Patent, is:—

An aspirator having a water inlet and a water outlet, a tubular member between the inlet and the outlet comprising an inlet section and an outlet section, said inlet section being flared inwardly and downwardly and said outlet section being flared outwardly and downwardly, the taper of said flared inlet section being greater than the taper of the outlet section, the relative 15 tapers of the two sections causing a fluid passing from said inlet section to said outlet section to impinge upon said outlet section, the bore of the outlet section being greater than the bore of the inlet section at the junction of said sections, said junction being free from obstructions which will deflect the flow of the fluid passing therethrough, and an air inlet in said outlet section positioned above that portion upon which a fluid passing from the inlet section to the outlet section will impinge.
